United States Patent Office

Des. 178,888
Patented Oct. 2, 1956

178,888

OCCASIONAL BARREL CHAIR

John J. Keal, Los Angeles, Calif., assignor to Capital Chair Company, Culver City, Calif.

Application April 12, 1955, Serial No. 35,476

Term of patent 3½ years

(Cl. D15—1)

Fig. 1

Fig. 3

I claim:

The ornamental design for an occasional barrel chair, substantially as shown.
